UNITED STATES PATENT OFFICE

JOHN HUSBAND, OF MONTREAL, QUEBEC, CANADA

ROTARY VALVE

Application filed September 10, 1926. Serial No. 134,729.

This invention appertains broadly to new and useful improvements in internal combustion engines and has more specific reference to a novel and simplified rotary valve 5 for use in connection therewith.

The primary object of the present invention is to improve generally the construction of valves of the character stated whereby to provide a valve structure of increased 10 efficiency and durability, one which is extremely simple in its construction and which can be manufactured at a small cost and one which can be incorporated with internal combustion engines of one or a plurality of 15 cylinders.

Another object of the present invention is to provide such a rotary valve which constitutes both an intake and an exhaust manifold and further to provide a novel partition wall for separating the intake and 20 exhaust manifolds.

Another object of the present invention is to provide such a valve which may have 25 associated therewith blower fans disposed in the intake and exhaust manifolds.

With these and numerous other objects in view, the invention resides in the novel construction, combination and formation of parts to be more clearly hereinafter described, and illustrated in the accompanying drawings and particularly pointed out in the appended claims.

In the drawings forming a part of this application:

35 Figure 1 is a view in elevation illustrating a further form of the present invention showing in elevation, a type of valve primarily designed for use in a multi-cylinder engine.

40 Figures 2 to 7 inclusive are transverse sectional views taken respectively on the lines 9—9 to 14—14 of Figure 1.

Figure 8 is a longitudinal sectional view taken through Figure 1.

45 Figure 9 is a transverse sectional view showing a still further modified form of my construction taken in exhaust position.

50 Figure 10 is a similar view showing the valve in intake position.

Figure 11 is a similar view showing the valve in compression position.

Figure 12 is a similar view showing the valve in the explosive position.

Figure 13 is a side elevational view of 55 the novel valve.

Figure 14 is a similar view showing an auxiliary valve sleeve employed in association with said valve, and

Figure 15 is a side elevational view showing 60 the valve and auxiliary sleeve in operative position.

By referring to the drawings it will be noted that in Figures 1 to 8 inclusive is disclosed the construction of the valve when used in connection with a six cylinder engine. In this form of the invention, the letter G generally indicates the cylinder head and H the improved valve associated therewith. The cylinder head, is, of course, 70 provided with a plurality of ports 50 which communicate with the cylinders of the engine.

The valve H comprises in its construction an elongated sleeve 51 which extends longitudinally within the cylinder head G, said sleeve being provided with a pair of openings 52 and 53 for each of the six cylinders, these pairs of openings being adapted for selective registration with the ports 50 in the operation of the valve. Arranged within the sleeve 51 and extending longitudinally thereof is a partition wall 54, the ends of which are oppositely directed as at 75 55 and 56 and formed integrally with said sleeve. The said partition wall serves to divide the interior of the sleeve to form the intake and exhaust manifolds 57 and 58. The partition wall 54 is also spirally 80 formed in the direction of its length and communicating with the intake and exhaust manifolds are the openings 52 and 53 hereinabove referred to.

While my improved valve structure has been illustrated in application as an overhead rotary valve, it is also readily applicable as a side valve mounted on the side of an engine.

95 The spiral formation of the partition wall 54 is an essential feature of the present in-

vention because it not only serves to bring the intake and exhaust manifolds over the engine ports at the proper time but also tends to draw in the fresh charge of fuel and expel the used charge.

With particular reference to Figures 9 to 15, wherein is illustrated another modified form of the invention, the letter K generally designates an engine cylinder head having a substantially cylindrical valve casting 59 formed thereon. A port 60 is formed in the cylinder head for the passage of combustible gases therethrough. This form of the invention embodies a main sleeve valve 61 of cylindrical form provided with a central partition 62. This main sleeve valve or rotor 61 is formed with a pair of spiral ports, comprising an intake port 63 and an exhaust port 64, terminating adjacent the rear end of the rotor.

Disposed between the rotor 61 and the casing 59 is a cylindrical auxiliary valve sleeve 65 formed with a plurality of staggered or alternately arranged ports 66 of rectangular formation, the sleeve being adapted to be rotated in reverse movement to the rotation of the rotor.

This valve structure is operated by means of beveled gears 67 and 68 mounted on the forward ends of the rotor and auxiliary sleeve respectively. When the rotor and sleeve 68 are in assembled position as shown in Figure 15, the forward end of the rotor projects substantially forward of the auxiliary sleeve so that the beveled gears 67 and 68 are disposed in parallel spaced positions. These gears are designed to mesh with a beveled pinion 69, fixed upon the upper end of a pinion shaft 70 which is suitably connected with the crank shaft of the motor.

In operation, if the rotor is arranged to rotate in an anti-clockwise direction, the auxiliary outer sleeve 68 rotates in a clockwise direction. The spiral ports 63 and 64 and the rectangular ports 66 are formed so as to selectively register in cooperation with the timing system to admit a combustible charge into the cylinders or permit escape of the exhaust. It will thus be noted that the partition 62 divides the main sleeve valve or rotor to form intake and exhaust manifolds, whereby the intake charge is conducted through the intake manifold into the cylinders and the exhaust carried through the exhaust manifold to the muffler.

Changes in details of construction may be resorted to without departing from or sacrificing the spirit of the invention so long as such changes fall within the scope of the appended claims.

What is claimed is:

1. A rotary valve for internal combustion engines including a cylindrical valve body having spiral ports formed therein and a

partition formed in the valve body providing intake and exhaust manifolds, a sleeve rotatably positioned about the valve body and formed with a plurality of ports adapted for selective registration with the main valve ports, beveled gears fixed on the forward ends of the valve body and sleeve, and a drive pinion in mesh with the said beveled gears to rotatably operate the valve body and sleeve in reverse rotary movement.

2. A rotary valve for internal combustion engines comprising a hollow cylindrical rotatable body having spiral intake and exhaust ports formed in its wall, a partition within the valve body extending longitudinally thereof and dividing the same to provide intake and exhaust manifolds with which the intake and exhaust ports are respectively in communication, a sleeve rotatably mounted upon the said body and having a plurality of intake and exhaust ports adapted for registration with the intake and exhaust ports of the said cylindrical valve body in the relative rotation of the parts, and means for imparting rotary motion to the valve body and sleeve in relatively opposite directions.

In testimony whereof I affix my signature in the presence of two witnesses.

JOHN HUSBAND.
